UNITED STATES PATENT OFFICE.

HERMAN SCHREIBER, OF DUNKIRK, INDIANA, ASSIGNOR TO THE OHIO FLINT GLASS COMPANY, OF OHIO.

DESIGN FOR A GLASS DISH.

SPECIFICATION forming part of Design No. 27,321, dated July 13, 1897.

Application filed May 24, 1897. Serial No. 637,965. Term of patent 7 years.

To all whom it may concern:

Be it known that I, HERMAN SCHREIBER, of Dunkirk, county of Jay, and State of Indiana, have invented a certain new and original Design for a Glass Dish; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to a design for a glass dish, and particularly to the ornamentation of the exterior surface thereof, of which the following is a specification, reference being had to the accompanying drawings, forming a part thereof.

In the drawings, Figure 1 is a plan view of a glass dish, showing my new design. Fig. 2 is a transverse vertical section on lines x x , Fig. 1.

The leading features of my design are a central quadrangular field in which is inscribed a circle bordered internally by four fan-shaped prismatic fields radiating toward the body of the dish and four ovoidal lines, the greatest diameters of which form their meeting point at the center of the dish, forming a quadrifoil and aped to border the base-lines of the fan-shaped prisms with checkerings in parallel relation with the base lines of the quadrangular field, from which radiate fan-shaped prisms with quadrant checkerings, and a checkered inward angled scalloped bordering in coincident lines with the scalloped beaded marginal surface.

1 designates a quadrangular field in which

is inclosed a circle 2, bordered internally by four fan-shaped prismatic fields 3, the prisms 40 of which radiate toward the body of the dish.

4 designates four ovoidal lines, the greatest diameters of which form their meeting point at the center 5 of the dish, forming a quadrifoil and aped to border the base-lines 6 of 45 the fan-shaped prisms with checkerings 7 in parallel relation with the base-lines of the quadrangular field, from which radiate fan-shaped prisms with checkerings 7 in parallel relation with the base-lines of the quadrangular field, from which radiate fan-shaped prisms 8 with quadrant-shaped checkered fields 9. Concentric to the quadrant-shaped fields 9 is a checkered inwardly-angled scalloped bordering 10, having minute prisms, 55 and coincident with the bordering 10 is a scalloped beaded marginal surface 11.

By reason of the plurality of fan-shaped fields with radiating prisms, with the right-angular checkered fields bordering the outer 60 prismatic field, there is produced a scintillation of light of pleasing effect, and by the refracting scintillation produced by the angled prismatic checkering of the border the effect is greatly augmented.

65 What I claim is—

The design for a glass dish, substantially as shown and described.

In testimony that I claim the foregoing as my own I hereby affix my signature in presence of two witnesses.

HERMAN SCHREIBER.
